UNITED STATES PATENT OFFICE

PAUL TISHKEN, OF DETROIT, MICHIGAN

GARAGE-DOOR BRACE

Application filed March 19, 1928. Serial No. 262,725.

This invention relates to door holders, and relates particularly to brace members or props adapted for pivotally mounting upon a hinged closure and obliquely engageable with a surface over which the closure swings to maintain the closure either fully or partially open.

It is an object of the present invention to adapt such a brace member to be held, by its own weight, out of use and vertically adjacent to the door on which it is mounted, and to provide a simple foot-operable mechanism for releasing it from said position.

Another object is to so pivot a brace bar upon a door that said bar may drop slightly on being swung to a substantially vertical inverted position, and may thereby assume a latched position, and to provide a foot-operable device adapted to first raise said brace member to permit its downward swinging and to thereby positively effect such a swinging.

These and various other objects the invention attains by the construction herein described and illustrated in the accompanying drawings, wherein:

Figure 1 is a view showing a door in cross section and showing in side elevation the herein-disclosed holder attached to said door.

Figure 2 is a plan view of the same.

Figure 3 is a sectional detail view, taken upon the line 3-3 of Figure 2, showing primarily a provision for releasing and lowering the brace member from its latched position.

Figure 4 is a vertical sectional detail of the same, taken upon the line 4-4 of the dash line showing in Figure 3.

In these views, the reference character 1 designates a door and 2 a surface over which said door swings. For holding said door open or partially so, I provide a brace member consisting of an elongated flat metal bar 3, having one end portion 4 pointed for non-sliding engagement with the surface 2 and having its other end pivotally attachable to the door 1 by a suitable bracket 5. Said bracket, which is secured to said door by screws 6 or the like, at a suitable distance above the surface 2, comprises a pair of par-

allel spaced lugs 7 projecting transversely to the door, between which lugs the bar 3 extends, a rivet 8 or other suitable member being secured in said lugs to pivotally mount said bar.

For retaining the bar 3 in its vertically inverted position shown in dash lines in Figure 1, an opening 9 formed in said bar to receive the rivet 8 has the nature of a slot elongated lengthwise of said bar, preferably relatively close to that edge of the bar which is undermost in the position of use of the bar. Thus, when the bar has been raised into vertical proximity to the door, said slot permits a slight bodily lowering of the bar to the position shown in dash lines in Figures 1 and 3, the rear edge of the bar being thereby engaged with a projecting portion 10 of the bracket 5 so as to prevent pivotal swinging of the bar.

To adapt the brace bar to be readily released from the position just described, the slotted end portion of said bar has one of its side faces uniformly depressed forming a shoulder 11 diagonally extending across the bar, as best seen in Figure 3, and within this depression a sheet-metal cam member 12 is eccentrically pivoted upon the rivet 8 in engagement with said shoulder and is integrally formed with a foot-lever portion 13 projecting substantially transversely to the bar and having a portion 13a thereof laterally bent to increase its foot-engageable surface.

In releasing the bar 3 from its raised position, it is necessary only to subject the lever 13 to a light foot pressure, whereby the cam 12 will first undergo a slight rotation such as to elevate the bar to the extent permitted by the slot 9. In this position, the bar is free to swing about the rivet 8, and is compelled so to swing by the leverage exerted against the shoulder 11. Thus the bar is positively actuated downwardly, and rests upon the surface 2, and the engagement of its pointed end with said surface positively restrains the door 1 from swinging shut.

When it is desired to close the door, the bar 3 may be raised to its latched position either manually or by lifting said bar upon the toe of the operator. The location of the slot 9

adjacent to the edge of the bar 3 remote from the base of the bracket 5 minimizes such rounding of the corner of the bar adjacent to said base as is requisite to allow the bar to swing after being raised to its dash line position.

The construction is light, simple, inexpensive and adapted to be quickly attached to a door.

10 While it will be apparent that the illustrated embodiment of my invention herein disclosed is well calculated to adequately fulfill the objects and advantages primarily stated, it is to be understood that the invention 15 is susceptible to variation, modification and change within the spirit and scope of the subjoined claims.

What I claim is:

1. The combination with a brace bar 20 formed at one end with a lengthwise slot, and a supporting bracket for said bar, of a pivot member carried by said bracket and passing through said slot, whereby said bar is adapted to be shifted bodily downward when swung 25 to an inverted vertical position, said bracket having a part co-acting with said bar in said downwardly shifted position of disuse to maintain said position, and means carried by said bracket for bodily shifting said bar upward to the extent permitted by said slot and for then positively swinging said bar toward its position of use.

2. The combination with a pivot pin of a brace bar, having a length-wise slot at one 35 end portion thereof, receiving said pin and affording the bar a limited length-wise travel relative to said pin, said bar having one side of its slotted end portion depressed, thereby forming a shoulder, a bracket carrying said 40 pin, a cam member mounted upon said pin within said depression of the bar, and engageable with said shoulder upon actuation about the pin axis to raise the bar bodily, relative to said pivot element, and adapted to 45 then act through said shoulder to initiate a downward angular travel of the bar and a pedally operable actuating member, carried by and projecting from, said cam member.

3. The combination with a brace member, 50 angularly movable from an inclined position of use to an up-standing position of dis-use, of a pivotal support member mounting said bar, one of said members being formed with a slot, a pivot pin carried by the other of 55 said members, and engageable in said slot, said bar being adapted by a limited raising and lowering in its up-standing position by travel of said pin in said slot, and said bracket co-acting with said bar in its lowered up-standing position to maintain such position, and means carried by said pivotal member 60 for raising said bar and for then initiating downward angular travel of said bar.

In witness whereof I hereunto set my hand.
PAUL TISHKEN.
